SHEET FEEDER

Headley Townsend Backhouse, London, England

Application December 4, 1937, Serial No. 178,129
In Great Britain June 26, 1937

4 Claims. (Cl. 271—53)

This invention consists of improvements in or relating to sheet feeders and is particularly but not exclusively concerned with automatic stream feeders for printing or like machines, i. e., feeders which supply sheets of paper, card or the like to the machine in the form of a continuous stream of partly underlapped sheets.

The invention has reference to the front lays which are normally provided for registering the sheets in position on the feed board before they are taken to the printing machine by means of grippers or the like. In one common type of printing machine the front lays operate above the feed board and, in turn, first engage and register in position the leading edge of each sheet and then move away to release the sheet for feeding to the printing machine. A difficulty which arises with this form of front lay mechanism is that should a sheet arrive on the feed board in advance of its correct time and position there may not be time for the front lays, after they have moved away from the registering position to release the preceding sheet, to return to that position before the leading edge of the abnormally advanced sheet has moved past the registering position. If this should happen then the advanced sheet may not be properly gripped by the feeding grippers and it may be taken into the machine in a torn and crumpled condition and possibly at the same time cause damage to the machine. It is an object of the present invention to provide improved mechanism by which this difficulty is overcome.

In the embodiment of the invention herein illustrated, a sheet-fed printing or like machine is provided with front lays operating as described above to register the leading edge of each sheet in turn and is characterized by one or more sheet-arresting devices operating from below the level of the feed board and arranged to be operative, during the whole or part of the time the front lays are moved out of the sheet registering position for the release of the leading sheet, to engage and prevent the feeding substantially past the registering position of a succeeding sheet.

In the preferred form of the invention the sheet arresting device comprises a stop or stops located close to the front lay registering position on the side thereof nearer to the machine in the direction of movement of the sheets and upwardly movable to a position above the level of the feed board to engage, and prevent further feeding movement of, a sheet which may be fed past the registering position until the front lays have returned to that position.

One specific embodiment of the invention will now be described by way of example and with reference to the accompanying diagrammatic drawings, in which:

Fig. 1 illustrates the mechanism in side elevation in the position of registration of a sheet by the front lays.

Fig. 2 is a similar view illustrating the position of the mechanism during the feeding of the sheet to the printing machine.

Fig. 3 is a similar view illustrating the engagement of a misplaced sheet by the gripping or holding device, and

Fig. 4 is an end view on the line 4—4 of Fig. 1. In this example the sheets 1 are fed down the feed board 2 from a stream feeder (which may be of the kind described in my copending application Serial No. 738,500, filed August 4, 1934) in partly underlapped formation. In the normal operation of the mechanism the leading edge of the top sheet is engaged as it reaches the end of the feed board by the front lays 3 which effect the longitudinal registration of the sheet. At the appropriate time in the cycle of operations of the printing machine the leading sheet is taken by grippers (not shown) and the front lays 3 swing about the axis 4 into the position shown in Fig. 2 and the sheet is transferred to the impression roll 5.

Shortly after the leading sheet has been taken by the grippers the hook-like stops 6 move upwardly into the position shown in Fig. 2, lifting the leading sheet off the feed board. Immediately after the trailing edge of the sheet has left the feed board the front lays 3 return to the registering position and in the normal operation of the machine they reach that position in time to engage the leading edge of the succeeding sheet. If, however, the succeeding sheet has been misplaced on the conveyor of the feeding mechanism its leading edge may arrive at the registering position and move past that position before there has been time for the front lays to return to it.

The sheet will, however, as shown in Fig. 3, be engaged by the stops 6 which are located closely adjacent to the registering position and which prevent substantial movement of the sheet past that position. This will occur even should the sheet have been misplaced to such an extent that it underlaps the trailing edge of the preceding sheet when it reaches the end of the feed board.

On the return of the front lays they may either push the sheet back into position or, depending upon the thickness and weight of the sheet,

slightly buckle it. In either case the sheet will be presented to the grippers of the machine in such a manner that it will pass through the machine without damage although it may be slightly 5 out of register. Immediately after the front lays have returned to the registering position the stops 6 move downwardly below the level of the feed board to allow the sheet to be taken by the grippers and moved over the stops.

10 The movement of the front lays and the stops may be effected from any suitable moving part of the printing machine or of the sheet separating and feeding mechanism. By way of example I have shown herein a shaft 10 upon which are 15 mounted two cams 11 and 12, cam 11 engaging a follower 13 carried by a bifurcated arm 14 which is pivotally connected with one of the front lays 3, the bifurcations straddling shaft 10 so as to be slidable thereupon but guided and supported thereby. Cam 12 acts upon a follower 15 carried upon one end of a crank arm 16 which is fixed to a shaft 17 upon which the stops 6 are also mounted. The shaft 10 is so driven as to have one revolution for each revolution of the impression cylinder 5, and it may conveniently be 20 the same shaft that operates detector mechanism (not shown) for stopping the printing machine should no sheet be presented at the proper time for feeding to the machine.

25 30 It is to be understood that the invention is not restricted to the precise constructional details set forth. Thus the front lays may be of the kind having a substantially vertical movement towards and away from the feed board. In that case the front lays will not operate to push back 35 a sheet which has been fed slightly too far and engaged by the stops, but the mechanism will prevent the over-feeding of the sheet by such an amount as to cause the grippers to fail to engage 40 it properly.

Having thus described my invention, I claim:

1. In mechanism for feeding sheets to a printing press or other sheet handling machine, a feed board over which the sheets pass, front lays 45 movable to a position at the forward end of said feed board for front registering the sheets one after another, and a sheet arresting device normally ineffective with respect to properly fed sheets arranged to move upwardly from a level beneath the feed board to a position above the feed board slightly in advance of the operative 50 position of the front lays and prior to the time the front lays assume their registering position to engage any misplaced sheet and prevent its

being moved forward on the feed board substantially past the registering position.

2. In mechanism for feeding sheets in lapped relation to a printing press or other sheet handling machine, a feed board over which the stream of sheets passes, front lays pivotally mounted above the forward end of the feed board to swing into position at the front end of the feed board for front registering the sheets one after another, and a sheet arresting device arranged to move 10 upwardly from a level beneath the feed board to a position above the feed board slightly in advance of the operative position of the front lays, whereby any sheet which is forwardly misplaced will be caught by said sheet arresting device and held against forward movement during at least 15 a portion of the movement of said front lays backwardly to sheet registering position.

3. In mechanism for feeding sheets to a printing press or other sheet handling machine, a 20 feed board over which the sheets pass, front lays movable to a position at the forward end of said feed board for front registering the sheets one after another, stops normally ineffective with respect to properly fed sheets mounted to move upwardly together from a position below the level of said feed board to a position above the level of the feed board slightly in advance of the operative position of the front lays and prior to the time the front lays assume their registering position, said stops being timed to move upwardly to their sheet arresting position after the front 25 lays have been withdrawn and before the rear edge of the next preceding sheet has passed the stops.

4. In mechanism for feeding sheets in lapped relation to a printing press or other sheet handling machine, a feed board over which the stream of sheets passes, front lays movable to a position at the forward end of said feed board for front registering the sheets one after another, stops normally ineffective with respect to properly fed sheets mounted to swing together upon a transverse axis below the forward end of said feed board upwardly to a position above the level of the feed board slightly in advance of the operative position of the front lays and prior to the time the front lays assume their registering position, said stops being timed to swing upwardly to their sheet arresting position directly after the 45 front lays have been withdrawn to permit the sheet to pass to the printing press or other machine.

HEADLEY TOWNSEND BACKHOUSE.
